STAND LAMP ASSEMBLY

Louis Ludwig, Brooklyn, N. Y.

Application March 18, 1940, Serial No. 324,607

5 Claims. (Cl. 287—20)

This invention relates to stand lamp assemblies, and more particularly to assemblies of shades, lamp-supporting brackets, and supports therefor. The prior usual practice has been to solder the shade to the support in order to prevent the shade from turning with reference to the support.

The objects of the present invention, among others, are: To provide an improved construction 10 of assembly for a lamp shade, a lamp bracket within the shade, and the end of a support; the support may be hollow and contain electrical wiring, which may pass thru the hollow end of the support and thru holes in the shade and the 15 lamp bracket and the wires suitably connected to the terminals of a standard electric lamp socket.

In one embodiment of the invention the lamp bracket has a flat arm, apertured near the end 20 and engaging the inside of the back of a shade, a shade having a flat back and centrally apertured, a hollow flexible supporting arm, a hollow nipple internally threaded at the outer end and secured against turning on the flexible arm, lugs 25 on the bracket arm projecting outwardly adjacent the aperture in the arm, extending thru the aperture in the shade and into recesses formed in the end of the nipple, and protrusions on the bracket arm on opposite sides of the arm aperture which extend into apertures on opposite 30 sides of the shade aperture, and a hollow arm adapted to thread into the nipple threads and having secured on the end a hexagonal head the 35 wall of which holds the assembly tightly together so that all of the assembled parts turn as a rigid unit with the end of the flexible supporting arm.

In another embodiment of the invention the same rigid assembly connection is mounted on the end of a hollow swivel which is supported on 40 the side of a vertical supporting arm at the top.

In an alternate assembly structure the hollow swivel or nipple end has opposite end recesses, the bracket arm has the same outward lugs, but the shade has slots on opposite sides of its central aperture thru which the arm lugs extend into the recesses in the end of the nipple, swivel, or other base support, in which case the arm protrusions and the apertures in the shade into 45 which they are adapted to fit may be omitted.

Other objects will appear as the description proceeds.

Reference is made to the drawing in which

Figure 1 is a front view with a front section of 55 the shade broken out.

Figure 2 is a section on the line 2—2 of Figure 1.

Figure 3 is a section on the line 3—3 of Figure 1.

Figure 4 is a view like Figure 2 but enlarged 5 and showing a swivel support.

Figure 5 is an enlarged transverse section thru the assembly and swivel support.

Figure 6 is like Figure 2 but showing an enlarged alternate assembly structure. 10

Figure 7 is a transverse section thru the assembly shown in Figure 6.

A shade 10 has a substantially flat, circularly apertured approximate the center, back wall. A standard electrical lamp socket 11 has the usual 15 internal screw threads and is adapted to mount an electric lamp (not shown) within the shade 10, and is itself supported on one arm of a right-angled bracket 12 which has an aperture for admission to the socket 11 of electrical wiring 13 20 which also passes thru an aperture 14 in the arm and into the socket 11. The long arm of the bracket 12 is flat and lies against the inside back wall of the shade 10, and near the end has an aperture concentric with the aperture 25 in the rear wall of the shade 10.

Referring to Figures 1, 2, and 3, a base 15 may have a conduit for the electrical wiring 13 and supports a hollow flexible arm 16, on the upper end of which is secured a hollow internally 30 threaded nipple 17, the outer end 18 of which is pressed upon the flexible arm 16 so as to securely grip it against turning thereon. The end of the nipple 17 is flat, lies against the outside of the back wall of the shade 10 around the 35 aperture, and has two diametrically opposed recesses 19 therein. Projecting outwardly from the long arm of bracket 12 at the edge of the end aperture therein are two diametrically opposed lugs 21 adapted to snugly fit in the recesses 19. 40 On opposite sides of the aperture in the long arm of bracket 12 are outer protrusions 22, spaced 90 degrees from the lugs 21, which enter apertures in the rear wall of the shade 10. A centrally apertured hexagonal nut 23 is wider than 45 the aperture in the long arm of the bracket 12 and heads the end of a hollow screw 24, the threads of which engage the internal threads of the nipple 17, and when the nut 23 is tightened the nipple 17, the shade 10, and the bracket 12 50 are locked together and against relative rotative movement. It will be noted that the assembly is easily and quickly made.

Referring to Figures 4 and 5, a rigid hollow supporting arm 25 supports near the top a lat- 55

5
eral projection 26 on which is mounted a hollow
swiveled nipple 27 externally roughened for
facile manual rotation, internally threaded, and
having diametrically opposed recesses 28 like
the recesses 21. The assembly is the same as
that shown in Figures 1, 2, and 3.

10
Referring to Figures 6 and 7, the outer pro-
trusions 22 are omitted from the outside of the
bracket 12 as are also the corresponding aper-
tures in the shade 10. Instead of the former
15 construction diametrically opposed slots 29 are
provided adjacent the shade aperture and the
bracket lugs 21 are passed thru slots 29 to hold
the shade 10, the nipple 17, and the bracket
15 arm 12 together against relative rotation when
the screw 23 and the nut 24 are tightened.

20
Having disclosed my invention and realizing
that, in view of my disclosure, many changes
or omissions or substitutions of parts will readily
occur to those skilled in the art, I do not limit
25 myself to the exact structure shown and de-
scribed.

I claim:

25
1. In an electrical lighting fixture, a substan-
tially flat apertured member, a second flat mem-
ber engaging one side of said apertured member,
an arm having an end engaging the other side
30 of said apertured member, a recess in said arm
end, a lug mounted on said second member and
extending into said recess and securing said
second member and said end against relative
rotation, and means for locking the assembly
35 together.

35
2. In an electrical lighting fixture, a substan-
tially flat apertured member, a second substan-
tially flat member engaging one side of said aper-
tured member, an arm having an end engaging
40 the other side of said flat apertured member, a
recess in said arm end, a lug mounted on said
second member and projecting thru said first
member and extending into said recess and se-
curing said second member and said end against
45 relative rotation, a protrusion on one member
engaging an aperture in the other member, and
means for locking the assembly together so that
each of the members and the arm end is posi-
tively locked against relative rotation.

50
3. In an electrical lighting fixture, a part hav-
ing a substantially flat portion surrounding an
aperture, a second part having a substantially

flat portion surrounding an aperture that is
concentric with the aperture in the first part
and engages one side of the first part, an arm
having a substantially flat end concentric with
the aperture in the first part and engaging the 5
other side of the first part, a recess in the arm
end, a lug fixed on the second part and ex-
tending thru the first part and into said recess
whereby the arm end and the second part are
10 secured against relative rotation, and means for
locking the assembly together.

4. In an electrical lighting fixture, a part
having a substantially flat portion surrounding
an aperture, a second part having a substan-
tially flat portion surrounding an aperture that 15
is concentric with the aperture in the first part
and engaging one side of the first part, an
arm, a nipple mounted on the arm and having
a substantially flat end concentric with the
aperture in the first part and engaging the other 20
side of the first part, a plurality of recesses in
said nipple end, a plurality of lugs fixed on
the second part and extending thru the first part
and into the recesses whereby the arm and the
second part are secured against relative turn- 25
ing, and means for locking the assembly to-
gether.

5. In an electrical lighting fixture, a part hav-
ing a substantially flat portion surrounding an
aperture, a second part having a substantially 30
flat portion surrounding an aperture that is
concentric with the aperture in the first part and
engaging one side of the first part, an arm, a
nipple mounted on the end of the arm and
having a substantially flat end concentric with 35
the aperture in the first part and engaging the
other side of the first part, a plurality of recesses
in said nipple end, a plurality of apertures in
the first part, a plurality of lugs fixed on the
second part and extending thru and fitting the 40
plurality of apertures in the first part and ex-
tending into and fitting the recesses in the nip-
ple end whereby the arm, the second part and
the first part are secured together against rela-
tive turning, and means for locking the assembly 45
together comprising internal threading in the
nipple and a screw threading into the nipple
and having a hexagonal head overlying and en-
gaging the inside of the second part.

LOUIS LUDWIG. 50
